DEVICE FOR CONVERTING BOTTLES, JUGS, OR VASES INTO LAMPS

Alexis Nihon, Nassau Bahamas, British West Indies

Application January 9, 1956, Serial No. 39,649

Term of patent 14 years

(Cl. D48—20)

Figure 1 is a perspective view of a device for converting bottles, jugs or vases, into lamps, showing my new design; and

I claim:

The ornamental design for a device for covering bottles, jugs or vases, into lamps, as shown and described.
